PAGE 3

FIG. 5

FIG. 6

FIG. 7

FIG. 8

FIGURE 1 is a perspective view of the building structure according to one embodiment of my new design;

FIGURE 2 is a front elevational view of the building structure of FIGURE 1;

FIGURE 3 is a side-elevational view of the building structure of FIGURE 1;

FIGURE 4 is a top plan view of the building structure of FIGURE 1;

FIGURE 5 is a perspective view of the building structure according to a second embodiment of my new design;

FIGURE 6 is a front elevational view of the building structure of FIGURE 5;

FIGURE 7 is a side-elevational view of the building structure of FIGURE 5; and

FIGURE 8 is a top plan view of the building structure of FIGURE 5.

The essential features of the design reside in the parts shown in full lines.

I claim:

The ornamental design for a building structure, substantially as shown and described.
